CAN OPENER

Peter J. Hughes, Plymouth Meeting, Pa.

Application October 17, 1952, Serial No. 315,225

6 Claims. (Cl. 30—16)

1

This invention relates to a can opener and, more particularly, to a can opener of the type adapted to be hooked under an end rim of a can and adapted, upon upward movement of a handle portion of the opener, to cut an opening in the flat top or end surface of the can.

The openers heretofore employed for cutting an opening in the end of a can have provided a triangular opening with a point of the triangle on the inward corner of the opening with respect to the end of the can and a base of the triangle parallel with a chord line extending across the end of the can and having this flat edge adjacent to the circumference of the can. These openers provide an opening in the end of a can by first piercing a hole at the radially innermost point of contact of the opener with the end of the can and thereafter progressively cutting the end of the can along two lines simultaneously extending from the innermost point outwardly to substantially the circumferential edge of the head of the can.

It is an object of the present invention to provide an opener which, upon operation, initiates a cut in the head of a can substantially adjacent to the circumference of a can, and thereafter cuts progressively generally toward the center of the can.

More particularly, it is an object of the present invention to provide a can opener by means of which an opening is provided in the head of a can which is cut first adjacent to the periphery of the can and then cut progressively inwardly from the periphery of the can along a first chord line extending across the head of the can and thereafter along a second chord line forming an angle with the first chord line for a distance sufficient that there is provided after the termination of the cutting a triangular opening in the can with one point of the triangle adjacent to the periphery of the can, the metal displaced from the triangle being turned downwardly from one of the edges of the triangular opening extending inwardly from the periphery of the can.

These and other objects of the invention will become apparent from the following description when read in conjunction with the accompanying drawing, in which:

Figure 1 is a perspective showing of the improved can opener;

Figure 2 is a top view of the opener shown in Figure 1;

Figure 3 is an end view of the opener shown in Figure 1;

Figure 4 is a perspective view of an alternate form of the type of opener shown in Figure 1;

2

Figure 5 is a top view of the opener shown in Figure 4;

Figure 6 is an end view of the opener shown in Figure 4;

Figure 7 is a view of the end of a can in which a cut has been made with the opener shown in Figures 1 and 2.

The opener, as shown generally at 2 in Figure 1, includes a strip of material 4 which is preferably a steel strip of rectangular cross section from which the opener is formed. Adjacent to one end of the strip there is provided an irregular shaped opening or notch 5 which provides a hook or a lip 6 which is adapted to engage the rim of a can when the opening 5 is placed over the rim of the can.

The cutter portion of the opener extends to the right from the opening 5, as viewed in Figure 1, and includes a portion 7 of the strip 4 which is bent at a slight angle to the strip along a bend line 8. The lower edge of the portion 7 of the strip is ground to form cutting edges of generally V formation extending outwardly from the opening 5 as indicated at 10 and 12. The cutting edges 10 and 12 join at a lowermost point 9. The cutting edge 12 extends outwardly from the lowermost point 9 and upwardly to the end of the strip portion 7 terminating in the region of approximately the center of the end of the strip. The upper portion 14 of the end of the strip is formed at an angle of slightly greater than 90° with respect to the portion 7 and extends from approximately the bend line 8 to the end of the strip. The outer generally horizontally extending portion 16 of the bent portion 14 is ground to provide a cutting edge which forms a continuation of the cutting edge 12 extending at an angle thereto. The portion 14 is bent toward the longitudinal axis of the strip 4 so that the cutting edge 16 extends across an extension of the longitudinal axis of the strip 4.

When the opener is employed, the hook 6 is engaged below the rim of a can and the left-hand end of the strip 4 is gripped by the user. The cutting edges are rotated about the rim of the can by upward force applied to the left-hand end of the strip 4. The base 9 of the V between the edge surfaces 10 and 12 pierces the end of the can in a region relatively close to the rim. Thus there is obtained for the initial piercing of the can a maximum mechanical advantage. After the initial hole is pierced, continued rotation of the handle will cause the cutting edge 12 to move downwardly and cut the surface of the end of the can progressively away from the rim of the can. When the entire blade portion 12 has cut

through the head of the can, the blade portion 16 of the flap portion 14 will commence producing a progressive cut in a transverse direction with respect to the direction of the cut produced by the cutting edge 12. This cut is progressively made due to the fact that the flap 14 is so formed that the end 16 thereof is at an angle of more than 90° to the end of the portion 7 of the cutter and the cutting edge 12 thereof.

During these latter two cuts, the cutting edge 10 will extend the originally pierced hole in the can outwardly to approximately adjacent to the rim of the can. Upon the completion of a cut, when the handle 4 is in an upward position of approximately 45° from the horizontal, the cutting edge 10 will be approximately parallel to the side wall of the can which extends from the end of the can in which the opening has been cut. A flap of metal cut from the end 46 of the can will be turned inwardly into the can, as indicated at 18 in Figure 7, and there will be provided in the can a triangular shaped cut having cut edges 20 and 22. The flap 18 extending inwardly from the head of the can will have been turned downwardly or inwardly by the flap portion 14 of the opener and no difficulty is experienced in removing the opener from the can after the opening has been cut.

An alternate form of the invention is shown in Figures 4, 5 and 6 in which a strip of metal 24 is provided with a cutout or notch 25 which provides a hook or lip 26 which is adapted to engage the rim of a can. A right-hand end portion 27 of the strip 24 is formed at an angle to the strip 24 along a bend line 28 which is inclined from a line extending transversely of the strip 24 and perpendicular to the longitudinal axis of the strip 24.

The edge of the portion 27 extending from the notch 25 is provided with ground cutting edges 30 and 32 in the arrangement similar to the cutting edges described in connection with the opener shown in Figure 1. The cutting edge 32 extends toward the end of the portion 27 of the opener. The cutting edge 30 extends toward the notch 25 and the two cutting edges meet at a lowermost point 31. The portion 27 of the opener is formed to provide a portion 34 at an angle thereto greater than 90° extending from the point at the end of the opener where the blade 32 meets the end of the opener and extending back to the bend line 28. The outer end of the portion 34 is ground to provide a cutting edge 36 which acts during the cutting operation as a continuation of the cutting edge 32. It should be noted that in this form of the invention the flap portion 34 is of considerable width adjacent to the bend 28 and a portion 38 of the strip 24 on the opposite side of the bend line 28 from the flap 34 is formed to extend outwardly from the strip in the opposite direction from that of the flap 34.

It will be evident that the two modifications described herein are merely minor variations of the invention. The relative angles of the various cutting edges and the relative lengths of the cutting edges may be selected as required depending upon the desired size and shape of the cut to be made in the can. Similarly, the angle of the bend line 8, in the opener shown in Figure 1, and the angle of the bend line 28, in the opener shown in Figure 4, may be selected to facilitate the forming of an opener having the necessary dimensions in order to provide an opening of a particular size and shape.

It will also be evident that the strips 4 or 24 in the openers shown in the drawings may be covered at their left-hand ends in order to provide an enlarged and more comfortable handle for the operator. Alternately, the left-hand end portions of each of these strips may be twisted so that the strip lies on a plane displaced 90° from the plane of the strip shown and thus a broad flat surface would be provided upon which pressure may be applied by the operator's hand when using the opener. While the opener has been described as preferably being formed of steel, it will be evident that the steel will generally be plated to provide suitable rust resistance or to provide resistance to chemical reaction with materials within the cans to be opened. These and other modifications may be made to the embodiment of the invention disclosed herein without departing from the scope of the invention as set forth in the following claims.

What is claimed is:

1. A device for producing an opening in the end wall of a container having an end rim comprising a handle, cutting means extending from one end of said handle, and means adjacent to the juncture of said handle and said cutting means for engaging the rim of the end of the container and providing a fulcrum about which said cutting means may be rotated by rotation of said handle thereabout, said cutting means comprising a cutting edge extending outwardly from said handle and having at its outer end a cutting edge extending sidewardly at an angle thereto.

2. A device for producing an opening in the end wall of a container having an end rim comprising a handle, cutting means extending from one end of said handle, and means adjacent to the juncture of said handle and said cutting means for engaging the rim of the end of the container and providing a fulcrum about which said cutting means may be rotated by rotation of said handle thereabout, said cutting means comprising a single cutting edge extending outwardly from said handle and having at its outer end a cutting edge extending sidewardly at an angle thereto of greater than 90°.

3. A device for producing a pouring opening in the end all of a container having an end rim comprising a handle, cutting means extending from one end of said handle, and means adjacent to the juncture of said handle and said cutting means for engaging the rim of the end of the container and providing a fulcrum about which said cutting means may be rotated by upward rotation of said handle thereabout, said cutting means comprising a vertically extending member having its lower edge formed with a cutting edge extending outwardly from said handle and a generally horizontally extending member provided along its outer edge with a cutting edge, the second mentioned cutting edge forming a continuation of the first mentioned cutting edge.

4. A device for producing a pouring opening in the end wall of a container having an end rim comprising a handle, cutting means extending from one end of said handle, and means adjacent to the juncture of said handle and said cutting means for engaging the rim of the end of the container and providing a fulcrum about which said cutting means may be rotated by upward rotation of said handle thereabout, said cutting means comprising a vertically extending member having its lower edge formed with a cutting edge of generally V formation as it extends outwardly from said handle and a generally horizontally extending member provided along its

outer edge with a cutting edge, the second mentioned cutting edge forming a continuation of the first mentioned cutting edge.

5. A device for producing a pouring opening in the end wall of a container having an end rim comprising a handle, cutting means extending from one end of said handle at an angle to the longitudinal axis of said handle, and means adjacent to the juncture of said handle and said cutting means for engaging the rim of the end of the container and providing a fulcrum about which said cutting means may be rotated by upward rotation of said handle thereabout, said cutting means comprising a vertically extending member having its lower edge formed with a cutting edge extending outwardly from said handle and a generally horizontally extending member provided along its outer edge with a cutting edge, the second mentioned cutting edge forming a continuation of the first mentioned cutting edge and extending across an extension of the longitudinal axis of said handle.

6. A device for producing a pouring opening in the end wall of a container having an end rim comprising a handle, cutting means extending from one end of said handle, and means adjacent to the juncture of said handle and said cutting means for engaging the rim of the end

of the container and providing a fulcrum about which said cutting means may be rotated by upward rotation of said handle about the rim, said cutting means comprising a vertically extending member having its lower edge formed with a cutting edge extending outwardly from said handle and having a first portion extending outwardly and downwardly from said means for engaging the rim of the container and thereafter extending upwardly to the end of the cutting means, said cutting means also including a generally horizontally extending member provided along its outer edge with a cutting edge, the second mentioned cutting edge forming a continuation of the outer end of the first mentioned cutting edge, said first portion of the first mentioned cutting edge being formed to lie substantially parallel to the side of the can extending away from the end of the can after the opening has been produced in the can by the first and second mentioned cutting edges.
